UNITED STATES PATENT OFFICE.

JOHN J. R. PATRICK, OF BELLEVILLE, ILLINOIS.

DEVICE FOR REGULATING TEETH.

SPECIFICATION forming part of Letters Patent No. 274,387, dated March 20, 1883.

Application filed November 8, 1882. (No model.)

To all whom it may concern:

Be it known that I, JOHN J. R. PATRICK, a citizen of the United States, and a resident of Belleville, in the county of St. Clair and State 5 of Illinois, have invented a new and valuable Improvement in Devices for Regulating Teeth; and I do hereby declare that the following is a full, clear, and exact description of the construction and operation of the same, reference 10 being had to the annexed drawings, making a part of this specification, and to the letters and figures of reference marked thereon.

Figure 1 of the drawings is a plan view. Fig. 2 is a perspective view. Fig. 3 is an enlarged detail section, and Fig. 4 is an enlarged perspective detail view.

This invention has relation to devices for regulating irregular and projecting teeth; and it consists in the construction and novel arrangement of parts, as will be hereinafter fully described, and particularly pointed out in the claims appended.

The object of this invention is to provide a simple and convenient instrument for rectifying 25 the position of teeth of either the superior maxillary or inferior maxillary, which, when properly arranged, will operate in a constant and automatic manner.

In the accompanying drawings, the letter *a* designates the body of the instrument, which 30 is made of half-round wire, preferably composed of an alloy of fifteen parts of gold and one of platinum, drawn down hard to the required thickness. The body *a* may be made of steel 35 wire treated in the same manner. The wire is bent in bow form, so as to embrace with its flat surface the dental arch, the extreme ends of the wire being designed to rest gently on the external lateral surfaces of the first or second 40 molars, as the case may require. The wire is provided with slides *b* and *c*, which embrace it accurately, so as to move steadily. To these slides various connections or bearing appliances are attached. In the drawings the 45 slides *c* are represented as carrying wedges *w*, hooks *h*, of various lengths and of different elevations and depressions, horizontal hooks, and loops *l*. Single and double T-hooks are also employed, as well as various special bearings 50 designed to suit the exigencies of par-

ticular cases. The slides *b* are provided with threaded bearings *d* to receive the boss-headed set-screws *e*, the ends of which are designed to bear against the bow, thereby securing the slides in position after adjustment. The slides 55 carry the loop-bands *g*, which are fitted to the teeth, which they are designed to embrace, and furnish, in connection with the slides and set-screws, ready means of fastening the instrument when in position. By these devices the 60 fixed bearing-points for the elastic bow *a* are formed.

The power of the instrument is in the elasticity of the bow-shaped wire or spring *a*, which is designed to operate through the medium of 65 the bearings at *g*, and the hooks *h*, wedges *w*, or other appliances upon the tooth or teeth to be moved. The action of the spring may be a kind of elastic leverage, or the direct inherent pressure of the spring may be utilized; or the 70 spring may have a greater bend than that of the dental arch, and may operate by its expansive force.

In some cases the pressure-points can be changed without releasing the set-screws—as, 75 for example, when the bearing loops or bands *g* embrace the second bicuspids and the extremities *z* of the spring rest on the first molars, if the extremities of the bow are bent inwardly so as to press on the molars, then the 80 second bicuspids become the resistance or the bodies to be moved. When any one of the six front teeth projects beyond the dental arch, and the wedges *w* are brought to bear on the projecting tooth, or when the bow-shaped 85 spring, without the wedges, is made to bear thereon, the pressure is the same, the wedges, however, serving as means whereby the tension can be increased from time to time without moving the set-screws. When externally- 90 projecting teeth are to be moved inward the bow-spring should be adjusted so that its flat surface touches all projecting teeth and then securely fastened by the set-screws and bands. The wedge or wedges are then brought to bear 95 on the projecting teeth, and are from time to time moved up until they cease to act. The wedges are then moved back, the spring taken up and reset firmly by means of the holding-bands and set-screws. If the bow-spring has 100

a tendency to slip toward the gum, a hook connected to one of its slides is snapped over the cutting-edge of a tooth and serves to hold it in position. As a rule, however, when the front teeth are found projecting outside the arch the premolars will be found repressed or inside the arch. Therefore, in order to widen the arch in a lateral direction, the loop-slides *l* should be connected to the first premolars, in addition to the securing-bands *g*, which embrace the second premolars, and the ends of the bow-spring should be bent inwardly to bear against the first molars. This will cause the power to be exerted by expansion in the region of the premolars, pulling them laterally outward, and to a less extent pressure will be exerted inwardly upon the projecting incisors. In cases where the alveoli, and palatine processes of the superior maxillary are constricted in the region of the premolars and molars, the bow-spring should be first adjusted so as to touch all the teeth when at rest. Then the loop-slides and fastening-bands are put in place, the bow-spring placed against the slides and marked to indicate their position, the loops and bands then removed and put in place on the bow-spring. The bow-spring should now be expanded and sprung to its place, when its lateral expansion will perform the work. When the premolars and molars are outside the arch the bow-spring should be laterally compressed and secured to the laterally-projecting teeth. It will then act by constriction, and will gradually repress the teeth, moving them inward to

their proper position. When the anterior or six front teeth are on the outside of the dental arch and are to be moved inward, the length of the bow-spring in front of the fastening-bands must be taken up from time to time by sliding its branches back in the slides of said bands and resetting the screws. If the anterior teeth are within the arch and are to be moved outward, the bow-spring must be let out or adjusted forward from time to time. These changes can be made without removing the instrument from the mouth, as the bow-spring and set-screw slides are outside the line of teeth.

What I claim, and desire to secure by Letters Patent, is—

1. An adjustable elastic arch-bar having the general form of the dental arch, and provided with sliding band-fastenings and set-screws, and with slides carrying loops, wedges, hooks, and other appliances, substantially as specified. 55

2. An adjustable elastic arch-bar having the general form of the dental arch, and provided with sliding band-fastenings, and with slides carrying hooks, loops, wedges, and other appliances, substantially as specified. 60

In testimony that I claim the above I have hereunto subscribed my name in the presence of two witnesses.

JOHN JOSEPH RAVENSCROFT PATRICK.
